The ornamental design for a toothbrush holder, as shown and described.

DESCRIPTION

FIG. 1 is a perspective view of a toothbrush holder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross-sectional view thereof taken at line 8 in FIG. 6; and,

FIG. 9 is another perspective view thereof, shown in use with its environment.

The environmental toothbrush and toothpaste tube shown in broken lines form no part of the claimed design. The dot-dashed arrows in the FIG. 6 view are used to identify the cross-sectional view, are for reference purposes only, and form no part of the claimed design.
